UNITED STATES PATENT OFFICE.

LEE J. MACGLASHAN, OF MOTLEY, MINNESOTA.

IGNITION SWITCH AND SAFETY DEVICE.

Application filed November 30, 1923. Serial No. 677,807.

This invention relates to a combination ignition switch and safety device and has for its primary object the construction of a device which may be manually operated and automatically regulated according to the oil pressure of the motor.

An object of the invention is the novel manner of constructing and associating the various parts so that the switch may be manually operated for closing the ignition circuit and as long as the motor is running and creating proper oil pressure the switch will remain closed but upon decrease of the oil pressure below a predetermined degree the switch will automatically open for stopping the engine.

A feature of my invention is the simplicity of construction and novel manner of associating the various parts.

Another object of the invention is the construction of an ignition switch which is automatically closed by oil pressure created as the starter operates the motor eliminating the necessity of manual operation unless so desired.

Another object of the invention is to provide a device that is positive and unfailling in operation so as to positively prevent leaving the ignition switch closed when not in motion.

Another object of the invention is the construction of a device which will bring the ignition switch under control of oil pressure thereby bringing the two most vital functions of the motor under the control of a device positive in its operation.

With these and other objects in view the invention will be better understood from the following detailed description taken in connection with the accompanying drawing wherein:

The figure is a vertical sectional view of the device.

Again referring to the drawing illustrating one of the many constructions of my invention the numeral 1 designates a casing in which is arranged a flexible diaphragm 2 which divides the interior of the casing into front compartment 3 and rear compartment 4. The rear compartment 4 is adapted to receive a quantity of oil under pressure through the oil pipe 5 which communicates with the oiling system of a motor. Arranged in the front compartment is my novel construction of switch 6 which comprises a movable contact 7 connected to the dia-

phragm, and a stationary contact 8 arranged in the plate 9 of insulating material which is connected to the front of the casing. A stem 10 projects from the movable contact 7 through the plate 9 and has attached thereto an operating knob 11. The contact 7 is provided with screw threads in cooperation with the nut 12 arranged to vary the pressure of a spring 13 which constantly acts to separate the contacts. I have illustrated a diagrammatic view showing a portion of the ignition circuit 14.

From the foregoing description taken in connection with the accompanying drawing it will be seen that when the knob 11 is pulled forward to pull the contacts in engagement the ignition circuit is completed so that the motor may be started. Upon starting of the motor pressure of the oil in compartment 4 will increase and extend and flex the diaphragm 2 the required degree to hold the contacts in engagement. This condition will continue to exist as long as the motor is operated and oil pressure is correct but upon lowering of the oil pressure below a predetermined degree the diaphragm will move towards normal position to expand the action of spring 13 and thus the contacts are opened for breaking the ignition switch circuit and stop the motor.

It is, of course, to be understood that the invention may be constructed in various other manners and the parts associated in different relations, therefore, I do not desire to be limited in any manner except as set forth in the claim hereunto appended.

Having thus described my invention what I claim is:

An ignition switch and safety device including a casing, a diaphragm confined in the casing and dividing the casing into front and rear compartments, a contact element carried for movement with the diaphragm and including a stem, an insulating plate through which said stem extends carried by the casing, a contact element carried by the insulating plate and adapted for engagement with the first mentioned contact element, a spring member engaging the insulating plate and embracing the first mentioned contact element, a member carried by the first mentioned contact element and adapted for adjustment longitudinally thereof and engaging the spring member and adapted to vary the tension of the spring member upon adjustment thereof, an

operating knob carried by the stem for moving the diaphragm forwardly within the casing to enlarge the rear compartment, said diaphragm being normally disposed in a position to bring the first mentioned contact element into contact with the second mentioned contact element by the pressure of fluid confined in the rear compartment and adapted to move in a direction to disengage

the second mentioned contact element from the first mentioned contact element by action of the spring member upon decrease of the pressure of the fluid within the rear chamber, and means for supplying fluid to the rear compartment.

10
15 In testimony whereof I affix my signature.

LEE J. MacGLASHAN.
